UNITED STATES PATENT OFFICE.

WALTER KIESER, OF CHARLOTTENBURG, GERMANY, ASSIGNOR TO GENERAL ELECTRIC COMPANY, A CORPORATION OF NEW YORK.

ELASTIC-FLUID TURBINE.

1,085,136.

Specification of Letters Patent.

Patented Jan. 27, 1914.

Application filed June 27, 1912. Serial No. 706,127.

To all whom it may concern:

Be it known that I, WALTER KIESER, a citizen of the Swiss Republic, residing at Charlottenburg, Germany, have invented 5 certain new and useful Improvements in Elastic-Fluid Turbines, of which the following is a specification.

This invention relates to elastic fluid turbines, and its object is to produce a compact 10 machine in which are combined two independent turbines, one of which is a high pressure engine supplying its exhaust steam to a heating or other industrial system, while the other is adapted to extract the 15 energy of the steam fractionally in a plurality of stages connected to a condenser. Both turbines are mounted on a common shaft from which the combined power developed by both machines can be transmitted 20 to suitable driven mechanism. The low pressure side of the tapped turbine is connected not only to the heating or other industrial system, but also to a low pressure chamber of the condensing turbine, so 25 that the latter derives a portion of its power from the exhaust steam of the former. By the combination of the two turbines in one casing a reduction in the length of the entire machine is obtained, and by reason of 30 the absence of unnecessary walls and bearings the cost of manufacture is considerably reduced.

The accompanying drawing is a diagrammatic sectional representation of a turbine 35 embodying the construction above set forth.

The high pressure turbine is shown as consisting of but one bucket wheel 1 mounted on a shaft 2 and inclosed in a casing 3. A partition 4 cuts off a portion of said casing to 40 form a chamber for the wheel 1 which receives steam through one or more nozzles 5 located in said partition and communicating with a chest or drum 6 which is connected with the live steam main 7. The remainder 45 of the casing forms a chamber for the condensing turbine, which has a plurality of bucket wheels 8 all mounted on the shaft 2 and alternating with the diaphragms 9 which separate the several stages. The 50 highest stage receives steam from the drum

6 through one or more nozzles 11. The lowest stage communicates by the exhaust pipe 10 with a condenser (not shown).

The admission of live steam to the two turbines may be effected otherwise than by 55 means of the common drum 6, so as to afford opportunity for separate regulation of the two machines, if desired.

Preferably the greater portion of the exhaust from the high pressure turbine 1 flows 60 off through a pipe 12 to a heating or other industrial system. But the remainder of such exhaust escapes through a nozzle or nozzles 13 to a suitable stage of the condensing turbine. In the drawing, this 65 nozzle is shown as located in the partition between the two chambers of the casing, and delivering low pressure steam to the first stage of the condensing turbine.

In accordance with the provisions of the 70 patent statutes, I have described the principle of operation of my invention, together with the apparatus which I now consider to represent the best embodiment thereof; but I desire to have it understood that the apparatus shown is only illustrative, and that 75 the invention can be carried out by other means.

What I claim as new and desire to secure by Letters Patent of the United States, 80 is:—

1. The combination of a turbine casing, partition means dividing said casing into two chambers, a high pressure turbine in one chamber and a condensing turbine in the 85 other chamber, a steam chest in the turbine casing with nozzles opening into both of the chambers for supplying steam to each of the turbines, there being also nozzles for discharging part of the exhaust steam from 90 the high pressure turbine to a stage of the condensing turbine, and outlet means from the high pressure turbine for diverting part of the exhaust steam therefrom to a heating or other industrial system. 95

2. The combination of a turbine casing, partition means dividing said casing into two chambers, a high pressure turbine in one chamber and a multi-stage condensing turbine in the other chamber mounted on a 100

common shaft, a steam chest in the casing with nozzles at opposite sides thereof for supplying high pressure steam to each of the two turbines, nozzles in the partition means aforesaid for delivering part of the exhaust steam from the high pressure turbine to a stage of the condensing turbine, and outlet means for conducting a portion

of the exhaust steam from the high pressure turbine to a heating or similar system. 10

In witness whereof, I have hereunto set my hand this 7th day of June, 1912.

WALTER KIESER.
